PROCESS FOR DEWAXING HYDROCARBON OILS

Earl Petty, Hempstead, N. Y., assignor, by mesne assignments, to Sun Oil Company, Philadelphia, Pa., a corporation of New Jersey

Application January 13, 1933, Serial No. 651,497

18 Claims. (CL 196—18)

My invention relates to a novel process for removing wax from a wax-oil mixture or removing oil from a wax-oil mixture. This process is commonly referred to as "dewaxing."

My process takes advantage of the diluent, anti-solvent effect of certain very low boiling hydrocarbons such as propane, butane, ethylene, propylene, butylene. These hydrocarbons are gases at normal temperatures and pressures. By compressing the hydrocarbons and removing the heat of compression, it is possible to liquefy them very readily. The liquid hydrocarbons have the property of dissolving oil from a wax-oil mixture. At certain temperatures, these hydrocarbons may act as selective solvents in that the oil will be dissolved while the wax will not. For purposes of clarity, I will refer to the low boiling hydrocarbons as propane, though it is to be understood that any suitable hydrocarbons may be used alone or in admixture with carbon disulphide, sulphur dioxide, methyl chloride, butyl alcohol, or the like.

In removing wax from hydrocarbon oils, crystallization of the wax in the oil is an important factor. This depends upon the concentration of the solution and the temperature of the mixture. By concentration of the mixture is meant the ratio of wax-oil to the diluent. Obviously, if the oil-wax is diluted by the addition of the diluent, concentration is varied, i. e. decreased, in such case. Likewise, the removal of heat can be controlled to vary the crystallization conditions.

In considering the crystallization problems which arise in the dewaxing of oil-wax mixtures, the viscosity effect of the diluent is also an important factor. I have found that generally the lower viscosity will give the better crystal. The dilution requirement in the period of crystal growth is of vital importance. It will be found that too large a percentage of dilution in the early stages of crystal development will result in the retardation of crystallization due to the solvent effect of the diluent on the wax. By this I mean that the excess of diluent will redissolve or retard the wax which it is being attempted to crystallize.

I have found that, by blending the oil-wax mixture with diluent to a minimum dilution requirement consistent with the fluidity requirements for handling through heat exchangers, that I am able to control the concentration and obtain the most propitious crystal development. I have also found that, if the crystal is developing materially in the early stages of its growth by the use of proper concentrations I can obtain a further and continued crystal growth and separation of wax from the oil-wax mixture by subsequent chilling and dilution. The subsequent chilling and dilution can be carried out by the addition of propane which has been chilled independently to a

temperature lower than the chilled oil-wax diluent mixture. This further chilling of the propane before dilution of the mixture is necessary to give the proper solidity of crystal so that it can be handled for separation by transfer equipment without redissolving of the wax by the diluent and the oil. The propane is chilled to a sufficiently low temperature to act as a diluent without dissolving the wax. In other words, at a sufficiently low temperature, the propane exhibits the properties of a selective solvent, admixing freely with the oil and diluting it while leaving the wax substantially undissolved.

It will be appreciated that by chilling an oil-wax diluent mixture of a minimum concentration necessary for handling that the wax crystal growth is well started and that, to subsequently obtain the proper dilution to facilitate the separation by the addition of pre-cooled propane, I am enabled to obtain a more complete and a more expeditious separation of wax from an oil-wax mixture than has hitherto been possible. The dilution of the oil-wax mixture is accomplished in a series of stages, as will be herein-after more fully pointed out.

In general my invention contemplates the admixing of propane or some like liquefied hydrocarbon with an oil-wax mixture in sufficient quantity to give the necessary dilution for handling through a heat exchanger equipment. The mixture is first chilled by heat exchange with the dewaxed oil-diluent mixture, the wax-diluent mixture or both. The oil-wax-propane mixture may be then chilled to a lower temperature by one of several methods. I may employ heat exchange through expanding propane or refrigerating gas as a cooling agent. I may expand propane in direct contact with the oil-wax-propane mixture. The chilled oil-wax-propane mixture is then passed to a mixing chamber. Meanwhile I separately chill propane to a very low temperature by evaporating a portion of the liquefied propane so that the remainder of the propane becomes chilled by the evaporation. I then mix this chilled colder propane with the pre-cooled oil-wax-propane mixture. It will be observed that the addition of the chilled propane has a double effect as it will act as a diluent to reduce the concentration of the oil-wax-propane mixture. Secondly, because it is so cooled in and of itself, the temperature of the resulting mixture will greatly lessen. This combination of further chilling and an increase of dilution results in the precipitation of well developed wax crystals and/or amorphous wax which starts because of the dilution and the low temperature. I then filter the mixture thus prepared. I can precipitate more wax and extract more oil by the addition of a further quantity of chilled diluent to the remainder of the mixture. This results in a fur-

ther separation due to an increase in the dilution and a decrease in the temperature. After filtration, I recover the diluent from the oil-diluent and wax-diluent mixtures respectively.

In the accompanying drawings which form part of the instant specification and which are to be read in conjunction therewith and in which like reference numerals are used to indicate parts in the various views:

Figure 1 shows a schematic view of one form of apparatus capable of carrying out the process of my invention.

Figure 2 shows a schematic view of another form of apparatus capable of carrying out the process of my invention.

More particularly referring now to the drawings and especially Figure 1, liquid propane which has been compressed leaves tank 1 through line 2. A portion of the propane passes through line 3 to a propane evaporator cooler 4, the purpose of which will be hereinafter more fully described. Another portion of the propane passing through line 2 passes through branch line 5 and branch line 6 where it joins the oil-wax mixture coming from tank 7 from which it is being pumped by pump 8 through line 9. The propane from line 6 and the oil from line 9 admix in line 10 and pass to mixer 11 which may be provided with suitable motor driven paddles. Heat exchangers 12, 13, and 14 permit a pre-cooling of the oil-wax-propane mixture. The wax solution, that is the wax-propane mixture, passes from line 15 through heat exchangers 14, 13, and 12. This wax-propane mixture leaves heat exchanger 12 through line 16. At this stage of the process, the portion of wax-oil and propane is about 1 to 1 by volume. In other words, the oil-wax-propane mixture contains about 50% waxy oil and about 50% of propane. The pre-cooled oil-wax-propane mixture leaves heat exchanger 14 through line 17 and passes through heat exchangers 18, 19, 20, 21, and 22 in succession. The oil solvent mixture coming from the filters through line 23 is the cooling medium used in heat exchangers 18, 19, 20, 21, and 22. The oil-wax-propane mixture leaves heat exchanger 22 through line 24. In this line the temperature of the oil-wax-propane mixture will vary from zero to minus 20° F. It will be remembered that propane evaporator-cooler 4 is being supplied with liquid propane through line 3 under pressure. A portion of the propane in evaporator cooler 4 may be released through line 25 by manipulating valve 26, the propane vapors passing to the separator 27 from which the gaseous propane is removed through line 28 and passed to compressor 29 in which it is compressed to form a liquid. The liquid is then pumped through line 30, through suitable cooler-condenser 31, through line 32, to storage tank 1. Any ungasified propane which may escape through line 25 by priming is separated in separator 27 and returned to the evaporator 4 through line 33. The evaporation of a portion of the body of propane in evaporator 4 serves to cool the remainder of the propane present in the receptacle. I have found it a very simple matter to chill the body of propane in evaporator cooler 4 to temperatures between -40° and -50° F. A portion of the propane from branch line 5 passes through branch line 34 to heat exchangers 35, 36, and 37. These heat exchangers are connected in series, heat exchanger 37 being connected by valved line 38 to the compressor 29. It will be appreciated that the propane passing through the heat exchangers 35,

36, and 37 will be allowed to expand and, in so doing, chill the fluid passing through the other side of the heat exchangers.

As pointed out above, the temperature of the oil-wax-propane mixture in pipe 24 will be from 0° F. to -20° F. If desired, the concentration may be altered and the temperature lowered at this point by introducing a portion of the chilled propane from propane evaporator cooler 4 into oil-wax-propane mixture flowing in line 24. This can be easily done by means of line 39 which is controlled by valve 40. It will be observed that heat exchangers 35, 36, and 37 are indirect expansion coolers. The material leaving heat exchanger 37 through line 41 will be at a temperature of about -30° to -40° F. This material is conducted through line 41 to mixing chamber 42. A line 43 communicates with the propane evaporator coolers and is controlled by valve 44. In the mixing chamber the oil-wax-propane mixture is admixed with a supply of chilled propane from evaporator cooler. It will be recalled that the temperature of the propane is between -40° F. and -50° F. In this mixing chamber 42, the dilution and the lowering of the temperature will cause further solidification of wax crystals already formed, the formation of additional wax crystals and wash the oil from the wax. The mixture leaves the mixing chamber 42 through valved line 45 and passes to filter section 46 which is provided with a plurality of filter screens 47. The filtrate passing from filter section 46 through line 48 will have a temperature of about -35° F. and will consist of about 70% propane and 30% oil. The wax and the oil-wax-propane mixture which contains such wax as has not been rendered filterable leaves filter section 46 through valved line 49 and passes into second mixer 50. In the second mixer a fresh supply of pre-chilled propane passes through line 51 which is controlled by valve 52. Here again a fresh crystallization and precipitation takes place due to the continued action of the lowering of the temperature and the decreasing of the concentration of the oil-wax mixture. The mixture then passes to filter section 53, through valved line 54. The filtrate leaves filter section 53 through line 55. This will have a lower temperature than that leaving the section above. For example, it will be about -37° F. and will consist of about 80% propane and 20% oil. The bottoms from filter section 53 pass through valved line 56 and into mixer 57 where a fresh supply of chilled propane is admixed with the solution. The propane enters the mixer through line 58 which is controlled by valve 59 and communicates with the propane evaporator cooler 4, as will be readily seen by reference to the drawings. The filter area in filter section 60 to which the mixture now passes through line 61 is somewhat larger than the filter area in the preceding section. The filtrate is removed through lines 62 and 63. It will have a temperature of about -40° F. and will consist of about 90% propane and 10% oil. It will be noted that in each filtrate withdrawal line 48, 55, 62, and 63, I have placed a three-way cock 64, 65, 66, and 67. The filtrates may be collected in the common line 68 and be passed to filtrate receiver 69. A portion of the filtrate may be collected in receiver 70 from which it may be pumped by pump 71 through line 72 for recycling through line 24.

It will be noted that a line 73 adjoins the three-way cocks 64, 65, and 67. This line acts as a clearing line. By this I mean a line through

which a menstruum may be circulated to clear the filters. After the device has been in operation for a while, wax will collect on the filter screens. By closing valve 74 and operating pump 75 and setting the three-way cocks, filtrate may be pumped from tank 69 through line 76 to line 73 and thence through the filtrate drawers in reverse direction enabling the filter screens to be cleared. If desired, gas may be injected through line 77 which is controlled by valve 78, it being understood of course that the three-way cocks have been previously set. In this manner, gas will be made to pass through filtrate drawoff lines 48, 55, 62, and 63 to clear the filter screens. It is to be understood, of course, that any suitable method of clearing the filter screens may be used: for example, the filter screens may be rotatably mounted adjacent scrubbers so that mechanical separation may be resorted to. This is but a minor detail and forms no major part of the instant invention, though it is essential that the filter screens be not allowed to become clogged. The wax solvent mixture leaves the bottommost filter chamber 60 through valve controlled line 80 and passes into wax-propane mixture tank 81.

It will be observed that the three filter sections 46, 53, and 60 are placed in superposed relationship to form a single column. This is done for purposes of convenience only and it is to be understood that the filter chambers may be placed in any suitable relationship. The basket centrifuge will remove the crystalline wax which will pass into wax receiver 85 through line 86. The wax slurry from the last stage of the filter passes from receiver 81 through line 82 by means of pump 83 and is delivered to basket centrifuge 84. In this type machine the granular or crystalline wax can be separated and discharged through pipe 86 into tank 85 and from thence be pumped directly to wax petrolatum stabilizer 88. The remainder of the mixture of wax-propane-oil will leave the basket centrifuge through line 87 and pass into line 15 through heat exchangers 14, 13, and 12 through line 16 to stabilizer 88. Stabilizer 88 is provided with a stripping coil 89 which will strip the propane-wax slurry of the propane which passes through overhead line 90 to cooler 91 and thence to propane tank 1. The mixture of propane and oil and wax combined which is delivered from the basket centrifuge as a liquid through the pipe 87 contains mostly propane admixed with some oil and wax. This mixture can be sent through the exchanger system as indicated and the propane then separated in a stabilizer such as 88, or it can be recirculated as blending diluent in mixer 11 to make up part of the original dilution requirement, thus recovering the refrigeration directly instead of through the exchangers and thus saving the step of de-propanizing, at least part of this wash recovery. The filtrate from tank 69 is pumped normally by pump 75 through line 76 and line 23, it being understood that valve 74 is open and valve 79 is closed. The oil-propane mixture passing through line 23 will have a temperature of between -20° to -40° F. The wax slurry passing through line 82 will have a temperature of about -30° F. The oil-propane mixture from line 23 will pass through heat exchangers 22, 21, 20, 19, and 18, through line 92 to stabilizer 93 which is provided with a steam coil 94 which will strip the propane from the dewaxed oil. The propane passes overhead through line 95 where it joins propane from sta-

bilizer 88 in line 90 and is cooled in condenser 91 and passed to storage in propane tank 1. The petrolatum wax is withdrawn from stabilizer 88 through line 96 and passed to storage. The dewaxed oil is withdrawn from stabilizer 93 through line 97 and passed to storage.

Referring now to Figure 2, the process is identical with certain minor changes which will now be described. The oil-wax-propane mixture leaving heat exchanger 22 through line 24 passes into a crystallizer evaporator 100. Propane evaporator cooler 4 is supplied with propane from propane tank 1 through line 3 which joins line 34. Line 34 is provided with a branch line 101 which is controlled by a valve. This line supplies propane to crystallizer evaporator 100. The oil-wax-propane mixture which passes into crystallizer evaporator 100 through line 103 is diluted with the propane entering through line 101. By opening valve 104 and allowing a partial release of the pressure, the evaporation of a portion of the propane will chill the oil-wax-propane mixture in crystallizer evaporator 100. If desired, a portion of the chilled propane from evaporator cooler 4 may be introduced into crystallizer evaporator 100 through line 105. The chilled oil-wax-propane mixture leaves crystallizer evaporator 100 through line 106 and passes to mixer 107. This mixer may act as a further crystallizer evaporator, if desired, by the addition of a line 108 provided with a valve 109 opening into a separator 110 from which the pressure is released. Normally, however, valves 109 and 111 are closed so that mixer evaporator 107 acts exactly the same as mixing chamber 42 of Figure 1. It will be observed that line 43 controlled by valve 44 permits the addition of chilled propane to the mixing chamber 107. The process from here on is identical with that previously described and like reference numerals will be used to indicate like parts as pointed out above.

An oil having a viscosity of 50 at 210° was dewaxed according to my process with the following results:

- I. Charge— 50 sec. viscosity at 210° F.
94 sec. viscosity at 130° F.
165 sec. viscosity at 100° F.

50	Oil component after removal of solvent	Wax component after removal of solvent	
Vis. at 210° F. seconds	47	Vis. at 130° F. seconds	138
Vis. at 130° F. ....do....	93	Vis. at 210° F. ....do....	56
Vis. at 100° F. ....do....	164	Melting point °F.	110-112
Yield .....percent	90	Yield .....percent	10
Cold test °F.	0		

Another oil, which I will call No. II was dewaxed according to my process with the following results:

- II. Charge— 145 sec. at 210° F.
1050 sec. at 100° F.

65	Oil component after removal of solvent	Wax component after removal of solvent	
Vis. at 210° F. seconds	140	Vis. at 210° F. seconds	158
Yield .....percent	92	Yield .....percent	8
Cold test °F.	0	Melting point °F.	115

No. I oil could not be dewaxed by the conventional method. No. II oil was dewaxed by the conventional method using naphtha and gasoline as a diluent and chilling followed by a centrifugal

or gravity separation of the wax with the following results:

II. By conventional method.

Charge— 145 sec. at 210° F.
1050 sec. at 100° F.

Oil component after removal of solvent	Petrolatum wax component after removal of solvent
Vis. at 210° F. seconds... 147	Vis. at 210° F. seconds... 130
Yield..... percent... 84	Yield..... percent... 16
Cold test ..... °F... 0.5	Melting point... °F... 130-135

A comparison of oil No. II as dewaxed by my process and dewaxed by conventional methods will clearly show the advantages and improved results obtained with my process; likewise, oils such as No. I above, which cannot be dewaxed by conventional methods, may be dewaxed by the use of my process.

The improved results in yield and quality of the oil are due to the selective anti-solvent effect of the propane for certain high viscosity material of the asphaltic or resinous character. This material is retained in the wax and causes the low melting point and high viscosity of the wax obtained by my dewaxing process, even though the wax be very concentrated. Pure wax, if completely isolated from the oil, would have a relatively low viscosity, for example, 32-40 sec. at 210° F. In separations which give a large oil loss to the petrolatum, the viscosity of the petrolatum at 210° F. is lowered by the wax viscosity effect. When propane is used, however, there is a lower oil loss and petrolatum yield. The oil which goes with the wax is of an entirely different series and has such a high viscosity that the low wax viscosity is completely offset.

It will be observed that the distinguishing characteristic of the instant process is the cooling of propane by itself. This cooling is accomplished, it will be observed, by the evaporation of a portion of a body of propane. This chilled propane is then added to an oil-wax-propane mixture of fairly high concentration with the result that the diluent is increased simultaneously with the lowering of the temperature. I am enabled, by means of this step, to obtain many of the improved results herein pointed out. It will be observed that I have accomplished the objects of my invention. I am enabled to dewax hydrocarbon oils substantially completely to obtain a very low cold test with a high yield of oil.

It will be observed further that pressure is required to keep the propane in a liquid state so that the filtering operation is conducted under pressure.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. A method of dewaxing hydrocarbon oils, including the steps of diluting a waxiferous hydrocarbon oil with a hydrocarbon diluent, cooling the mixture without increasing the dilution to a temperature at which wax crystals are devel-

oping materially, then adding a hydrocarbon diluent to the mixture, said hydrocarbon diluent being prechilled to a sufficiently low temperature and being added in such quantity as to lower the temperature and increase the dilution of the mixture at once to a condition where filterable wax crystals are formed and then filtering the crystals from the mixture.

2. A method of dewaxing hydrocarbon oils including the steps of diluting a waxiferous hydrocarbon oil with propane, cooling the mixture without increasing the dilution to a temperature at which wax crystals are developing materially, chilling a body of propane to a predetermined lower temperature by evaporating a portion of the same, adding a portion of the body of chilled propane to the mixture in sufficient quantity to simultaneously increase the dilution and lower the temperature of the mixture to cause additional wax precipitation, filtering the mixture to obtain an oil-diluent component and a wax-diluent component, recovering the diluent from the components to obtain a dewaxed oil and wax.

3. A method of dewaxing hydrocarbon oils in which a mixture is formed of wax-bearing hydrocarbon oil and a diluent and the mixture chilled without increasing its dilution to a temperature at which wax crystals are developing materially, chilling a body of liquefied normally gaseous diluent to a temperature lower than the chilled mixture and bringing the chilled oil-wax mixture to a lower temperature by injecting the chilled liquefied diluent whereby additional wax is precipitated.

4. A process of separating readily filterable wax from oils containing wax which comprises, mixing said oil with a liquefied normally gaseous hydrocarbon in an amount sufficient to render the mixture fluent at the dewaxing temperatures, chilling the mixture to a temperature of about 0° F. or below to precipitate wax, adding sufficient precooled solvent to render the final mixture readily filterable and filtering the precipitated wax from the diluted oil.

5. A process as claimed in claim 4 in which the liquefied normally gaseous hydrocarbon is liquid propane.

6. A process as claimed in claim 4 in which the chilling temperature is -10° F. or below.

7. A method of dewaxing hydrocarbon oils including the steps of diluting a waxiferous hydrocarbon oil with only sufficient hydrocarbon diluent to permit handling through heat exchanger equipment, cooling the wax-oil-diluent mixture to a predetermined temperature at which wax crystals are developing materially, separately chilling a body of propane to a temperature below the temperature of the mixture, adding a portion of the chilled propane to the mixture in sufficient quantity to increase the dilution and to lower the temperature of the mixture to precipitate additional wax, filtering the mixture to obtain an oil-diluent component and a wax-diluent component, performing said first mentioned cooling step by passing said first mentioned mixture in heat exchange relation with one of said components and recovering the diluent from the components to obtain a dewaxed oil and wax.

8. A method of dewaxing hydrocarbon oils including the steps of blending a wax bearing oil with propane to a minimum dilution requirement consistent with the fluidity requirements for handling through heat exchangers, passing the mixture through a chilling zone in indirect

heat exchange with colder fluid to thereby chill the mixture to a predetermined temperature at which wax crystals are developing materially, effecting a decrease in the concentration of the mixture in the later stage of its travel through said chilling zone as compared to the concentration of the mixture in the early stage of its travel through said zone by adding propane to the mixture as it enters such later stage, adding to the chilled mixture issuing from said chilling zone colder propane in a quantity sufficient to further solidify the wax crystals formed and further decrease the concentration of the mixture whereby more expeditious wax separation may be obtained and separating the mixture into an oil-propane component and a wax-propane component.

9. The process of claim 8 in which one of said components is employed as colder fluid in said chilling zone.

10. A method of dewaxing hydrocarbon oils including the steps of blending a wax bearing oil with propane to a minimum dilution requirement consistent with the fluidity requirements for handling through heat exchangers, passing the mixture through a chilling zone in indirect heat exchange with colder fluid to thereby chill the mixture to a temperature at which wax crystals are developing materially, effecting a decrease in the concentration of the mixture in the later stage of its travel through said chilling zone as compared to the concentration of the mixture in the early stage of its travel through said zone by adding a colder diluent liquid to the mixture as it enters such later stage, adding to the chilled mixture issuing from said chilling zone colder propane in a quantity sufficient to further solidify the wax crystals formed and further decrease the concentration of the mixture whereby more expeditious wax separation may be obtained, separating the mixture into an oil-propane component and a wax-propane component and recycling to the mixture being chilled a portion of the oil-propane component as said earlier mentioned colder diluent liquid.

11. A method of dewaxing hydrocarbon oils including the steps of blending a wax bearing oil with propane to a minimum dilution requirement consistent with the fluidity requirements for handling through heat exchangers, passing the mixture through a chilling zone in indirect heat exchange with a colder fluid to thereby chill the mixture to a temperature at which wax crystals are developing materially, adding to the chilled mixture issuing from said chilling zone colder propane in a quantity sufficient to further solidify the wax crystals formed, precipitate additional wax and further decrease the concentration of the mixture whereby more expeditious wax separation may be obtained, separating the mixture into an oil-propane component and a wax-propane component, centrifugally separating the crystalline wax from the wax-propane component and blending at least some of the cold residual portion of the wax-propane component with the oil to be dewaxed to assist in initially diluting the oil and effect an initial temperature reduction of the oil by direct heat exchange.

12. A method of dewaxing hydrocarbon oils including the step of blending a wax bearing oil with propane to a minimum dilution requirement consistent with the fluidity requirements for handling through heat exchangers, passing the mix-

ture through a chilling zone in indirect heat exchange with colder fluid to thereby chill the mixture to a temperature at which wax crystals are developing materially, adding propane to the chilled mixture issuing from said zone, chilling the mixture to a lower temperature by evaporating a portion of the propane, chilling the mixture to a still lower temperature to precipitate additional wax by adding separately chilled propane at a temperature lower than the temperature of the mixture and separating an oil-propane component from the mixture.

13. A method of dewaxing hydrocarbon oils including the steps of dissolving a wax bearing hydrocarbon oil in a diluent and reducing the temperature of the mixture by indirect heat exchange to a temperature at which wax crystals are developing materially, chilling a body of liquefied, normally gaseous hydrocarbon diluent to a temperature lower than the chilled mixture by evaporating a portion thereof, and further chilling the partially cooled mixture to a lower temperature by injecting said chilled liquefied hydrocarbon diluent therewith.

14. A method of dewaxing hydrocarbon oils including the steps of forming a mixture of a wax-bearing hydrocarbon oil and a diluent, chilling the mixture to a temperature at which wax crystals are developing materially, bringing the mixture to a lower temperature by injecting thereinto a sufficient amount of colder chilled diluent whereby additional wax is precipitated, separating a portion of the wax free oil from the mixture and bringing the mixture to a second and lower wax precipitating temperature by injecting additional colder chilled diluent thereinto.

15. A method of dewaxing hydrocarbon oils including the steps of diluting a waxiferous hydrocarbon oil with only sufficient diluent to permit handling through heat exchanger equipment, cooling the mixture to a predetermined temperature at which wax crystals are developing materially, further diluting the mixture by adding thereto a sufficient quantity of diluent, said diluent being prechilled to a temperature below the temperature of the mixture, and separating the wax from the mixture.

16. A method of dewaxing hydrocarbon oils including the steps of diluting a waxiferous hydrocarbon oil with only sufficient hydrocarbon diluent to permit handling through heat exchanger equipment, cooling the mixture to a predetermined temperature at which wax crystals are developing materially, separately chilling a body of propane to a temperature below the temperature of the mixture, adding a portion of the chilled propane to the mixture in sufficient quantity to increase the dilution and to lower the temperature of the mixture to precipitate additional wax, filtering the mixture to obtain an oil diluent component and a wax diluent component, and recovering the diluent from the components to obtain a dewaxed oil and wax.

17. A method of dewaxing hydrocarbon oils including the steps of cooling a propane wax oil mixture to a temperature at which wax crystals are developing materially, adding to the chilled mixture a propane like diluent chilled below the temperature of the mixture while maintaining the mixture under pressure, separating under pressure a portion of the oil from the mixture, adding additional chilled propane like diluent below the temperature of the partially de-oiled mixture to the mixture and separating under pressure additional oil from the mixture.

18. In a method of dewaxing hydrocarbon oils in which a normally gaseous liquefied hydrocarbon is used as a diluent, chilling an oil-diluent mixture to a temperature at which wax crystals are developing materially, separately chilling a 5 liquefied normally gaseous hydrocarbon to a temperature below the temperature of the chilled oil-diluent mixture, adding a portion of the

chilled hydrocarbon to the mixture to precipitate additional wax, filtering a portion of the oil from the mixture, adding a further amount of colder chilled hydrocarbon to the partially deoiled mixture to further reduce the temperature and further increase the dilution to precipitate additional wax and filtering the oil from the mixture.

EARL PETTY.
